UNITED STATES PATENT OFFICE

WILLIAM K. MCNAIR, OF CLOQUET, MINNESOTA, ASSIGNOR TO THE NORTHWEST PAPER COMPANY, OF CLOQUET, MINNESOTA, A CORPORATION OF MINNESOTA

CLAMPING MACHINE

Application filed March 23, 1932. Serial No. 600,810.

The present invention relates to clamping methods and devices, and particularly to a device called a header. Although the device may have numerous uses, it is specially adapted for clamping a cylindrical roll endwise. The preferred embodiment, as hereinafter described is specially adapted for rolls or spools, in which there is an axial bore, such as is found in a roll of paper wound on a hollow core, or a tube. Inasmuch as the invention has been developed with reference to a problem encountered in wrapping rolls of paper with a protective covering it will be described with reference to that problem, without any intention to limit to that field the utility or the construction of devices embodying the invention.

In the manufacture of paper and like sheets large and heavy rolls of the material are formed. Ordinarily such rolls are wound on hollow cores of tubular structure. Such rolls may be moved about by overhead cranes having tongs or equivalent devices, the free ends of which are inserted into the hollow core. They are also moved about by rolling, as on the floor. Where high grade papers are used, care must be exercised to keep the paper clean. Where the paper is cut to a prescribed width for special use, care must be exercised to protect the edge of the roll. For example, a roll should not be placed on its end, for in so placing it, or in placing it on its side from an endwise position, as may be done manually, the edge bears the weight of the roll, and paper is thus damaged at the edge for a considerable distance into the roll.

Where such heavy rolls are to be wrapped, they may be set down horizontally, as by a crane, onto a wrapping sheet and then rolled so that the wrapper may be picked up and wound about it, leaving projecting ends of the wrapper to be turned over on the ends. It is a custom to place a sealing disc of paper, such as a label, over the turned-in end of the wrapper at each end of the roll. To do this, pressure is applied against such a disc on the end.

Heretofore, two methods have been employed so to seal the wrapper on such rolls. One method is to move the roll into a heavy

machine between two clamping members. Machines for the purpose are available at great expense. They are heavy, and hence require a fixed location in the mill, to which location such rolls must be moved. The other method is to head one end and then stand the roll on end for creating the pressure. While pressure is thus applied the other end is finished, a seal applied, and the roll turned over to rest on the last-finished end. Such a process requires physical force of laborers and considerable time. It also injures the edge of the roll. It is not applicable to long rolls.

The present invention aims to seal, or head, the rolls with a minimum of time, labor and expense, without injury to the roll; to head the rolls wherever they may be; to head rolls of any length; and to dispense with the necessity for a large, heavy, costly and permanently located slow-operating, power-consuming machine.

One object of the invention is to place a prepared roll between two portable substantially vertical plates, then to draw the plates together, to lock them in a clamping action on the ends of the roll, and then to release the roll.

Another object of the invention is the provision of one, and preferably two, portable plates which are separable, and to clamp them together with a roll between them, by means of a single tension member passing through the hollow center of the roll.

Still another object is to provide a quick-acting lever or operating handle for bringing the plates into clamping engagement with a roll.

Still another object is the provision of a simple plate with a standard for holding it substantially vertical when it is idle.

Another object of the invention is the provision of a plate having a castor or similar wheeling construction associated with it to facilitate moving it from place to place.

Various other and ancillary objects and advantages of the invention will be apparent from the following description of the invention made in reference to the accompanying drawings showing an illustrative embodiment.

of the invention and the manner in which it is used for heavy rolls of paper. In the drawings:

Fig. 1 illustrates a roll of paper, wrapped and sealed in a usual manner, and it is such a roll as the described device is designed to form.

Fig. 2 is a front elevation of the device set for use.

Fig. 3 is a cross-section of a plate on the lines 3—3 of Fig. 2 and of Fig. 3.

Fig. 4 is a view of the outside of a plate as positioned in Fig. 2.

Fig. 5 is a plan view of the parts of Fig. 2, after moving into clamping engagement.

Fig. 6 is a front elevation of the parts shown in Fig. 5, illustrating the operating lever in locking position.

Fig. 7 is a perspective view of a suitable operating lever.

Fig. 8 is a perspective view of an adjusting wedge.

Fig. 9 is a view of a modified operating lever having a rolling ring for a cam.

Fig. 10 is a cross-section on line 10—10 of Fig. 9 showing the roller-bearing cam.

In Fig. 1 the roll shown has a hollow core 10. A wrapper 11 has its ends turned over in folds 12 over which is a seal or header 13 adhesively united to the folds. A supplementary sticker 14 is shown merely for the purpose of covering a hole 15 in the header caused by use of the device described. This sticker is not at all necessary, but it prevents presentation of any torn edges of paper.

A plate 16 may be formed of wooden planks suitably held together. At the bottom it carries brackets 17 and 18 which bear a wheel axle 19 carrying rollers 20 and 21. The brackets and rollers are so located that when the plate is vertical the rollers are off the floor, and so that when the rollers are on the floor the plate leans outwardly to a slight extent. Any suitable handle such as two pegs 22 and 23 may be provided. By holding such handles the plate may be readily wheeled about. Two similar plates are used in the preferred embodiment, so that both plates may be moved about with a maximum of convenience.

Where the plates are clamped with a single tension member, as can conveniently be done with a roll which has a hollow center, the center or other part of the plate has an elongated vertical slot 25 therein, into which a tension bar may slide. The vertical elongation permits adjustment of the position of the tension bar for different sizes of rolls. The slot 25 in wood is preferably protected from wear by the provision of a durable metal plate 26 on the outside. On the inside the slot 25 flares outwardly and the sides are protected with durable metal parts 27 and 28

forming a V-shaped entry to the slot. Plate 26 serves to hold together the wooden parts of the plate, and serves to protect plate 16 from strain.

A tension member is provided as a flat steel bar 30 with a series of detent recesses such as holes 31 along its length, and a hook-forming slot 32 on each end. The ends are made as duplicates to facilitate using either end of the bar with the holding and operating devices. A plurality of bars may be provided, but one long bar can be used and adjusted for the shortest roll available. The bar is adapted to enter the plate slots 25 at a height dictated by the size of a roll, and to project from each plate. The operating end 33 (Fig. 6) is close to one plate, and the holding end 34 may project without limitation. The holding end is fixed initially by means of a pin 35 through a hole 31. As clamping is effected, slack space is provided between the pin and the plate, and an operator then slides a forked wedge 36 between the pin and plate, and over the bar. The surface of the wedge 36 is preferably stepped as shown at 37 (Fig. 8), but this is not necessary where a sufficiently pointed wedge is used. The wedge preferably has two parts to encompass the bar, and a forked form is desirable to facilitate easy insertion and removal.

The operating end 33 has an operating device comprising a handle or lever 40 and a cam head 41. The cam is forked to encompass the bar 30, which enters space 42. Across space 42 is a fixed axis or pin 43 which may easily move into the hook-forming slot 32 in the tension bar. The cam surface 44 is substantially eccentric about the pin 43. When the lever 40 is near the vertical (full lines in Fig. 6) the cam surface and hence the plate may be nearer the pin 43. As the lever is moved toward the horizontal (dotted line position in Fig. 6) the cam surface is more remote from the pin and forces the plate away from the pin, thus putting tension on the bar. A flat spot 45 is desirable on the cam surface so that it serves to hold the parts in a substantially locked position when pressure is applied on the roll. Thus locked, the roll may be left clamped and the operator is free.

In Fig. 9 a modified cam construction is shown in which the cam surfaces 44 of Fig. 7 are formed by rings 48 having a roller-bearing relation to the heads 49 and 50 on the forked lever 51. A functional flat spot 52 is also provided.

In paper mills where many rolls are delivered to a shipping room, these may be aligned on a floor by a crane for rolling forward in succession. As each is rolled forward on the floor over a wrapper, the wrapper 11 may be wound on the roll. Then the end folds 12 are formed, and a pasted header or seal 13 may be placed loosely over the folds, or the folds may be cemented without such a seal

or header. The last operation may be performed just before the roll enters the space between the two plates, or even while the roll is in said space.

When the roll is properly centered to aline its hollow core with the slots 25, an operator thrusts bar 30 through one plate, through the hollow core, and it may easily find itself to project through the slot in the other plate.

- 10 The operator at the holding end inserts pin 35. Another operator quickly hooks the lever 40 into position and gives a clamping movement to the lever. This moves the plates closer together. He then lessens the operating pressure, and the first operator may place a device, such as wedge 36 either in place or moves it to a lower position on the bar. Then the lever may be operated again to give the final squeeze. The pasted label or header, or 20 end, is allowed to set for a very short period, when the parts may be released, the bar withdrawn, and the finished roll rolled away.

If desired, a suitable wedge may be used between the cam and the plate, thus permitting one operator to make all the movements necessary for operating the device. The wedge may be dispensed with by providing a cam which permits all the play necessary for operating the device. The spacing of the 30 holes in the bar bears upon the desirability of using the wedge.

The device does not require any setting or adjustment for a particular size of roll, except the movement of pin 35. It may be used on different sized rolls (either in length or diameter) in succession without inconvenience. It may be moved about as desired, is quicker in operation than known power machines, and is much cheaper to build and 40 to operate.

Although the device particularly described has a single tension bar, and this is used within the area of the plates, it is to be understood that this is merely illustrative, and is 45 a simple preferred form for rolls which are hollow. For other types of rolls, or other forms, it is to be understood that numerous changes can be made without departing from the invention.

50 Although it has been described with reference to rolls of paper, it may be used without change for rolls of cloth carpeting, and the like, when a hollow center is available. For these and for other other forms, obvious 55 changes can be made without departing from the spirit and scope of the invention as expressed in the appended claims.

I claim:

- 55 1. A clamping device comprising in combination two independent clamping plates, supports for each plate to maintain them substantially vertical, each plate being slotted in a vertical direction, a tension bar adapted to pass through the slots, locking means to secure the bar in tension at one

plate, and an operating device at the other plate effectively secured to said bar and adapted to move the plate along the bar towards the opposing plate.

70 2. A clamping device comprising in combination two plate members, a bar adapted to be connected for tension to each member, means to secure the bar in fixed connection to one plate, and an operating device for securing the bar adjustably to the other plate, whereby the adjustable connection effects a 75 clamping action between the plates.

80 3. A clamping device comprising in combination two slotted plates, a long bar adapted to enter both slots, said bar having periodic detent recesses therein, locking means adapted to engage in one of said detent recesses to secure the bar in tension to one plate, and an operating device adapted to engage one of said detent recesses at the other plate and adjustably secure said bar and said other plate in tension, the adjustable securing being effective as clamping action.

85 In testimony whereof I have hereunto affixed my signature.
